UNITED STATES PATENT OFFICE.

RICHARD E. HARPER, OF BUTLER, MISSOURI.

WHIFFLETREE-CLIP.

SPECIFICATION forming part of Letters Patent No. 288,796, dated November 20, 1883.

Application filed August 17, 1883. (No model.)

To all whom it may concern:

Be it known that I, RICHARD E. HARPER, of Butler, in the county of Bates and State of Missouri, have invented a new and useful Improvement in Whiffletree-Clips; and I do hereby declare that the following is a full, clear, and exact description of the same, reference being had to the accompanying drawings, forming part of this specification, in which—

10 Figure 1 is a plan view, and Fig. 2 a section on line x x of Fig. 1. Fig. 3 is a plan of the clip, and Fig. 4 a section thereof on line y y of Fig. 3.

15 My invention relates to improvements in whiffletree-clips; and it consists in the peculiar construction and arrangement of the parts, as hereinafter more fully set forth, and pointed out in the claims.

20 In the accompanying drawings, a represents a double-tree, preferably made oval on the rear edge of its back face, near its end, which gives it a better appearance than if a square edge were there formed, and better conforms with the curvature of the clip, hereinafter described.

25 b represents the improved clip, which consists of a brace or plate, c , preferably inserted in a mortise made longitudinally in the wood of the double-tree near its end, and bolted thereto, so that when the latter is painted it will not show, and also to hold the clip, of which it forms a part, securely in place.

30 d represents a plate, cast in one piece with the brace c , and passing once around the double-tree, whereby greater strength is attained than in the ordinary construction. The part of the plate d opposite the rear side

of the double-tree is reduced in width, and its upper end is enlarged at e , and provided with a hole, h , for the passage of a bolt, l , which 40 also passes through the central hole in the whiffletree w , and thence through the middle hole, m , in the brace c , thence through the double-tree and through the hole n in the clip b , thereby securely attaching the clip to the 45 double-tree. The bolt l is threaded at its lower end, and provided with a nut, o , to secure it in place. The upper end of the clip b projects sufficiently above the upper face of the double-tree to allow of the easy insertion 50 of the whiffletree between the clip and the upper face of the double-tree.

Having thus fully described my invention, what I claim as new, and desire to secure by Letters Patent, is—

55 1. The whiffletree-clip b , consisting of the longitudinal brace-plate c and transverse plate d , bent first vertically downwardly, then horizontally, then curved upwardly, and then horizontally over the plate c to its line of attachment with the latter, and provided with holes for the passage of the bolt l , as set forth.

60 2. The combination, with the double-tree a and whiffletree w , of the clip b , composed of the brace-plate c , bolted to the end of the 65 double-tree a , plate d , cast in one piece therewith, and passing once around the double-tree, and threaded bolt l , substantially as shown and described.

RICHARD E. HARPER.
